US00D790344S

(12) **United States Design Patent** (10) **Patent No.:** **US D790,344 S**
(45) **Date of Patent:** **** Jun. 27, 2017**

(54) **CLOSURE**

- (71) Applicant: **Silgan White Cap LLC**, Downers Grove, IL (US)
- (72) Inventors: **Darren Neputy**, Palos Hills, IL (US); **James M. Taber**, Aurora, IL (US); **Dennis A. Szczesniak**, Lemont, IL (US)
- (73) Assignee: **Silgan White Cap LLC**, Downers Grove, IL (US)
- (**) Term: **15 Years**
- (21) Appl. No.: **29/528,127**
- (22) Filed: **May 26, 2015**

Related U.S. Application Data

- (63) Continuation of application No. 29/497,467, filed on Jul. 24, 2014, which is a continuation of application No. 29/449,192, filed on Mar. 14, 2013, now Pat. No. Des. 712,744.

(57) CLAIM

We claim the ornamental design for a closure, as shown and described.

DESCRIPTION

FIG. 1 is a top perspective view of an embodiment of the claimed design;

FIG. 2 is a front view of the claimed design of FIG. 1, the rear view, the left side view and the right side view being the same as the front view;

FIG. 3 is a top plan view of the claimed design of FIG. 1; and,

FIG. 4 is a bottom plan view of the claimed design of FIG. 1.

The ornamental design which is claimed is shown in solid lines in the drawings. The broken lines in the drawings illustrate portions of the closure which form no part of the claimed design.
